UNITED STATES PATENT OFFICE

2,663,527

DISPLAY DEVICE

Stuart S. Joslyn, Chester, Conn., assignor to
 C. J. Bates & Son, Chester, Conn., a firm composed of Hamilton C. Bates, Wells C. Bates, and Hamilton C. Bates, Jr.

Application October 10, 1951, Serial No. 250,733

1 Claim. (Cl. 248—1)

1

This invention relates to improvements in display devices for jewelry and the like and has for its essential objects the provision of a means for displaying objects in a manner more conspicuous and more pleasing than that afforded by the ordinary and conventional display devices such as used by merchants in counter and/or window displays.

My invention offers the further advantage of providing a device which is readily collapsible or capable of being disassembled so as to occupy a minimum of space in packing and transporting and attains these ends in a structure which is easy to manipulate and simple and inexpensive to construct.

My invention relates to display devices generally and it has more particular reference to means for holding a sheet of fabric or the like whereby it can be effectively arranged as a covering material, the main object being to provide a simple, cheap and compact device which may be conveniently utilized for the purposes specified.

Broadly, the invention relates to a supporting and sustaining means for supporting and sustaining a sheet of fabric material and more particularly it is directed to one characterized by the feature of retaining such sheet with the desired degree of tension relative to the support member together with certain other features as will be hereinafter pointed out in this specification.

Another important object of the invention is to provide a device of the class described having a very simple and efficient construction, one which is reliable in its use, inexpensive in its manufacture, strong and durable, easy to manipulate and well adapted for the purposes for which it is designed.

Another objection to decorative or display devices of the types now available to merchants is that they are relatively expensive and are of such construction that it is difficult to obtain a variety of effects therewith.

By means of the structure of my invention, display devices or component pieces thereof may be economically produced. Further, they have an adaptability for convenient and easy adjustment of the relative parts whereby a plurality of different configurations or effects can be obtained with a minimum number of different component pieces. Thus my invention teaches an improved display device and method of producing the same which not only possesses all of the attributes of the old form of display device but also offers a

2

structure wherein the cost of manufacture thereof is materially reduced.

While the invention, for the sake of convenience, is illustrated as embodying a rectangular supporting member so as to produce rectangular shaped objects, it will be readily understood that the members may assume other desired shapes and it will be further understood that the device may be employed for purposes other than for display purposes or may be embodied in combination with other mechanisms and/or structures as will occur to those skilled in the art and therefore this invention finds a wide field of utility for other purposes than the specific ones herein discussed.

This invention is further characterized by the provision of a structure which may be produced in one of several ways and therefore as this description proceeds I will embody therein brief references to certain alternate preferred methods for making the device of this invention.

With the foregoing objects in view, my invention consists essentially of a support member having side and end edges transversely slotted to receive the end edges of support covering material adapted to be folded over the said support member, the same being so arranged as to provide a means for grippingly engaging the support covering material and holding it in the desired covering position.

All of the above objects I accomplish by means of such structure and relative arrangements of parts thereof, as will fully appear by a perusal of the description below and by various specific features which will be hereinafter set forth.

To the above cited and other ends and with the foregoing and various other novel features and advantages and other objects of my invention as will become more readily apparent as the description proceeds, my invention consists in certain novel features of construction and in the combination and arrangement of parts as will be hereinafter more particularly pointed out in the claim hereunto annexed and more fully described and referred to in connection with the accompanying drawings wherein:

Fig. 1 is a perspective view of the support member of the device of my invention;

Fig. 2 is an enlarged sectional view of one side of the support member of the device of my invention showing the cooperation of a fabric material therewith;

Fig. 3 is a sectional elevational view of the support member of the device showing a covering material associated therewith;

Fig. 4 is a perspective view of the display unit of the device of my invention in the assembled position; and

Fig. 5 is an end view of two of the support members held in fixed relation for display purposes.

Referring now to the drawings more in detail, the invention will be fully described.

The support member 10 of my invention comprises a section of an expanded plastic material which may be of any desired dimensions or shape depending on the particular purpose for which intended and/or effect desired to be obtained, all as will presently be observed.

The material used in the support member may be an expanded plastic material composed of cellular cellulose acetate, polyvinyl chloride, phenolic resin, or polystyrene.

These materials have each been introduced into the market in recent years and have the improved properties so desirable in the practice of my invention.

An expanded polystyrene, for example, has been announced. It is a snow-white, non-permeable, multicellular, foamed material having a buoyancy making it especially suitable for advertising displays and novelties. Being light in weight, the cost of its shipment is relatively small as compared with display devices heretofore made of wood, glass, or metal. The material is outstanding in working ability thereby facilitating fabrication or lay-up. Furthermore, if desired, it can be successfully bonded to wood, metal or various other materials as well as to itself. Adhesives and cements for such operations are numerous and readily available.

Cellular cellulose acetate, on the other hand, is a core material produced by extrusion. It is an oriented multicellular form of cellulose acetate developed to promote structural efficiency.

The plastic material in a condition of low viscosity is generally foamed by mechanical agitation with or without foaming agents. When solidified, the foamed mass retains its porous structure.

In some instances, the material is expanded by the action of a blowing agent. In other cases, a gas is dissolved in the soft plastic mass under relatively high pressure. Upon release of the pressure, the mass is made porous by the expanding gas. A subsequent hardening process fixes the porous structure.

Still another method of producing this material consists of incorporating a soluble solid in the plastic material. After molding, this solid is leached out by solvents.

In still another method of producing porous plastics, a fibrous or other bulky constituent is mixed with a binding substance to produce a porous product. The individual thermoplastic fibers are bonded together by action of heat or solvents.

Regardless of the procedure by which the expanded plastic is developed, the product is a plastic material which is currently available in the form of boards several inches thick and varying in lengths and widths.

A board of this kind can be readily shaped by conventional methods into any desired shape.

The extreme lightness of the material make it of great interest in the field of decorative window and counter displays.

The important feature of the expanded plastic as applied to my invention is that it is easily puncturable or rupturable. That is to say, it has

the capacity of being readily punctured by a pick or tool such as a knife, awl or the like. When, as will be presently observed, it is desired to pierce the member 10 as by a pin or other sharp pointed object, the pin may be made to remain erect at any desired angle relative to the member 10.

In other words, the material has the capability of being easily punctured by means of pointed metal or wooden rod members, which are tubular or square or any other desired shape in cross-section, and of retaining the same in any desired position relative thereto for any length of time.

The support member 10 is of substantially the shape in which it is illustrated in Fig. 1 although as aforesaid, it will be understood that other shapes can be used with varying results, obviously depending wholly on the desideratum relative to effect or appearance.

For example, instead of a rectangular shape, the member 10 could be square, triangular, heart, diamond shaped, all as may be desired. Then too, the member may be varied as to its third dimension so as to offer pyramids, cones and the like. Also, the side and end edges 11 of the member 10, instead of presenting parallel flat surfaces which are at right angles to the upper and lower faces as shown in Fig. 1, may be beveled or inclined or even curved with relation thereto.

The support member 10 is provided with a transverse slot or groove 12 upon each of its sides or edges 11 which slots are in horizontal planes and extend the entire length of each side. They are connected to each other so as to provide a continuous slot around all of the sides or edges of the member 10, substantially as shown in Fig. 1.

The slots are desirably of rectangular shape in transverse section with parallel upper and lower surfaces, the width therebetween being determined wholly by the thickness of the material to be receivable thereinto.

The slots are easily provided merely by means of a knife or similar sharp tool and have only such width and depth as to make it possible to insert therein the edge of a piece of fabric or like material whereby the same is held in a snug manner, as will be subsequently referred to.

In speaking of a fabric material, it will be understood that other materials such as leather, paper or the like having yieldable characteristics can be substituted therefor with equally satisfactory results.

In Fig. 2, I have shown the ends of two pieces of fabric or the like 14 and 16 which have been tucked into the slot 12 by means of a knife or similar sharp tool capable of being insertable into the slot so as to introduce the yieldable material thereinto so as to be retained therein as the tool is withdrawn.

The fabric having been inserted into the slot 11 on one side of the member 10, the fabric is of sufficient length as to be then brought over around the side and top of the member 10 and down the opposite side thereof to the slot 11 therein where the fabric is again tucked so as to provide a tight fitting cover over the area of the support member between the respective slots.

That is to say, the yieldable material is applied to the support member 10 as shown in Fig. 3 so as to extend across the top thereof and downwardly on the opposite sides and ends thereof to positions where the free edges of the yieldable material may be tucked into the respective slots and secured thereby.

The fabric is pulled over the surface of the member 10 to the desired degree of tautness by means of controlling the depth to which the material is inserted into the slot. By tucking the same tightly into the slots, it is possible to take up all of the slack. The fabric employed, of course, is of such dimension as to fit snugly over the area to be covered with only sufficient material as to permit the tucking to be accomplished.

The resilient nature of the support member will cause the edges of the fabric to be held within the slots.

This gripping action is aided by the fact that when the slots are made into the plastic material, the edges of the slots so produced are roughened due to the very nature of the material. The roughened surfaces of the slot permit an improved gripping or holding action on the fabric.

In Figs. 3 and 4, two pieces of fabric 14 and 16 are shown as covering a support member 10.

If desired, in order to create unusual effects, different colors or types of covering material may be used to cover a single block so as to produce an unusual effect consisting of a block covered with yieldable material of contrasting colors.

It will be further appreciated that the arrangement of parts is such that the entire support member including the corners may be completely covered and that there need be no projections of excess material on either the top or sides of the support member which extend outwardly therefrom when the structure is in the assembled position. This feature is of great value in allowing the device to be used in corners.

As a further feature of my invention, a pair or even more of the support members 10 may be covered as aforesaid. One or more connecting pins 20 are adapted to have their outer free ends puncturable through the yieldable fabric material and the support member in a puncturing manner whereby two or more support members are held relative to each other in any one of a myriad number of relative positions whereby is obtained a variety of display effects.

The invention may be embodied in other specific forms without departing from the essential characteristics thereof. Hence, the present embodiments are therefore to be considered in all respects merely as being illustrative and not as being restrictive, the scope of the invention be- 50

ing indicated by the appended claim rather than by the foregoing description, and all modifications and variations as fall within the meaning and purview and range of equivalency of the appended claim are therefore intended to be embraced therein.

What it is desired to claim and secure by Letters Patent of the United States is:

As a new article of manufacture, a display device comprising in combination, a unitary relatively rigid body formed from plastic material adapted to be impinged by implements, said body having opposite and adjacent side portions provided with a continuous relatively narrow groove therearound extending inwardly of said side portions and providing opposed substantially rigid friction faces at opposite sides of said groove, covering members formed from flexible material covering said body and disposed on the sides of said body with each of the adjacent marginal edges thereof in superposed relation in said groove and frictionally engaged by the friction faces thereof throughout the entire length thereof to hold said covering members from displacement on said body.

STUART S. JOSLYN.
